UNITED STATES PATENT OFFICE.

JOSEPH O. DIMMICK, OF DENVER, COLORADO, ASSIGNOR TO THE DIMMICK CONCENTRATING COMPANY, OF SAME PLACE.

ORE SIZER AND CLASSIFIER.

SPECIFICATION forming part of Letters Patent No. 678,551, dated July 16, 1901.

Application filed July 9, 1900. Serial No. 23,035. (No model.)

To all whom it may concern:

Be it known that I, JOSEPH O. DIMMICK, a citizen of the United States, residing at Denver, in the county of Arapahoe and State of Colorado, have invented a new and useful Skimming Device for Ore Sizers and Classifiers, of which the following is a specification.

This invention relates to that class of ore-separators in which the pulverized ore is classified through the agency of water—such, for instance, as shown in my prior patent, No. 653,568, granted July 10, 1900.

The object of my invention is to provide a skimming device for carrying off the slimes which accumulate upon the surface of the water in sizers and classifiers of the type referred to.

The invention will be more fully described hereinafter with reference to the accompanying drawings, in which the same is illustrated as embraced in a convenient and practical form, and in which—

Figure 1 is a longitudinal vertical sectional view showing my device as applied to a sizer and classifier. Fig. 2 is a plan view of my device removed from the sizer and classifier, and Fig. 3 is a vertical sectional view thereof.

Similar reference characters indicate the same parts in the several figures of the drawings.

The sizer and classifier with which my present invention is illustrated in Fig. 1 is fully shown and described in my prior patent previously referred to and will therefore be only briefly described here in order that the operation of my improved skimming device may be understood.

A tank, preferably V-shaped in cross-section, is provided with a trough N or other suitable inlet, through which the pulp from the stamps or pulverizer is delivered. Across the center of the tank is located a partition G, near the bottom of which is an opening provided with a vertically-sliding gate. The size of the opening may be regulated by sliding the gate up or down by means of a rod extending from the gate to a point above the tank. At approximately the center of the gate is inserted a tubular coupling or nipple having a valve J located therein. A rod H² is operatively connected to the valve J and extends up-

wardly above the top of the tank, permitting ready adjustment of the opening through the coupling. A flexible pipe K, slightly longer than the distance from the gate to the end 55 wall of the tank to admit of the free adjustment of the gate, extends from the coupling in the gate to a nipple projecting through the end wall of the tank. A valve L is provided in the nipple on the outside of the tank. A 60 series of transverse partitions divide the bottom of the tank into a number of chambers M, each of which is provided with a discharge-outlet M², passing through one of the side walls of the tank, near the bottom thereof. 65 These partitions are preferably of a height substantially equal to the portion of the center partition below the opening therein. The end of the tank is provided with an overflow-spout N².

Reference letters A indicate vertical posts forming part of the framework for supporting the tank.

My present invention comprises an attachment for conveying the slimes from the surface of the water to the exterior of the tank, where they may be delivered to a table or concentrating device. In the form of my invention illustrated I provide a skimmer which floats upon the surface of the water and which 75 is provided with a central opening below the water-level. A flexible pipe leads from such central opening to the exterior of the tank, which in the sizer and classifier shown in Fig. 1 may be accomplished by connecting the 80 pipe with the coupling or nipple which passes through the adjustable gate in the central transverse partition G.

The details of the skimming-disk are best illustrated in Figs. 2 and 3, in which C indicates a rim projecting upwardly from a bottom C⁵, which is preferably concave. Holes C² are provided in the rim C at suitable intervals, and an opening C³ is formed in the center of the bottom C⁵. A nipple C⁴ projects downwardly from the opening C³, to which is coupled one end of a flexible pipe D, the other end of which leads to the exterior of the tank, or, as shown in Fig. 1, to the nipple extending through the adjustable 95 gate.

A table or support E, having legs E², is

preferably though not necessarily placed upon the bottom C⁵ of the skimmer over the opening C³. The table E is adapted to support a weight F, which is of such size as to 5 submerge the openings C³ below the water-line, (indicated by letter B in Fig. 1.) The table is preferably open at the top to permit weights being added or removed to give the exact weight required.

- 10 The operation of my invention is as follows: The pulp is discharged into the tank, and the slimes, which are too light to be drawn down by the downward current, accumulate upon the surface of the water. These floating slimes 15 then pass through the openings in the rim of the skimmer, and thence through the opening in the bottom of the skimmer to the pipe, from which they are discharged to a separate table or concentrating device. The volume 20 which may be drawn off through the skimmer may be regulated by varying the weight F, so that the openings C³ will be more or less submerged, or by plugging up some of the openings C³ to produce the desired amount of 25 inflow. The conduit or pipe D being longer than the distance from the gate to the surface of the water allows the skimmer to adjust itself upon the surface of the water to any point to which the current may carry it. 30 The slimes and skimming device being controlled by the same influence will always be at the same point upon the surface of the water.

Although I have illustrated my present invention as applied to the sizer or classifier covered by my prior patent, it is equally applicable to other ore sizers and classifiers of the washer type. I do not wish to be understood as limiting my invention to the more or 40 less precise forms and details described, as I contemplate changes in form, the proportion of parts, and the substitution of equivalents as circumstances may suggest or render expedient without departing from the spirit 45 of my invention.

Having now fully described my invention, what I claim as new, and desire to secure by Letters Patent, is—

1. In combination with an ore-classifier, a 50 skimming-disk adapted to float, and compris-

ing a concave bottom, a central exit therein connected to a flexible valved conduit, said disk being provided with a perpendicular rim provided with perforations at intervals in its circumference; a table supported by legs over 55 the central exit, adapted to receive a weight or weights whereby the depth of submergence of the skimmer may be governed, substantially as described.

2. In combination with an ore-classifier 60 comprising a tank divided into chambers by a partition, a gate in said partition, a flexible conduit passing through said gate and one of the end walls of the classifier, and connected at its other end to a skimmer in the first 65 chamber, said skimmer comprising a bottom, perforated rim, and a table supported by legs over the central exit and adapted to receive weights to regulate the submergence of said skimmer, substantially as described. 70

3. In an ore-classifier, the combination with a skimming device, adapted to float, comprising a bottom having an outlet-opening therein, and an upwardly-projecting rim surrounding the bottom, and having inlet perforations 75 therethrough, of means for adjusting the weight of said skimming device whereby its submergence may be governed, and the position of said inlet perforations relative to the water-line so adjusted that the desired 80 volume of liquid may be drawn off through the skimming device, substantially as described.

4. In an ore-classifier the combination with a tank having outlets, of a floating skimming device, means for adjusting the weight of said 85 skimming device, a conduit leading from said device to the exterior of the tank, whereby the heavier particles of ore pass through the said outlets in the tank, while the slimes which accumulate on the surface of the water 90 are drawn off through the conduit leading from the skimming device, the volume of such slimes drawn off being determined by the degree of submergence of the skimming device, substantially as described. 95
